UNITED STATES PATENT OFFICE.

RICHARD H. MELZER, OF SYRACUSE, NEW YORK, ASSIGNOR TO TRIPLEX GARMENT PRESSER, INC., OF SYRACUSE, NEW YORK, A CORPORATION OF NEW YORK.

GARMENT-PRESSING MACHINE.

1,400,088.

Specification of Letters Patent. Patented Dec. 13, 1921.

Application filed September 29, 1920. Serial No. 413,559.

To all whom it may concern:

Be it known that I, RICHARD H. MELZER, of Syracuse, in the county of Onondaga, in the State of New York, have invented new 5 and useful Improvements in Garment-Pressing Machines, of which the following, taken in connection with the accompanying drawings, is a full, clear, and exact description.

10 This invention relates to certain improvements in machines for pressing garments involving the use of lower and upper pressing elements of similar form and size, one of which, as the upper element, is mounted 15 upon a vertical rocking support for movement toward and from the lower element in combination with means for actuating the rocking support, and additional means for supplying steam to the garment, preferably 20 through the lower element, and for heating both of the pressing elements.

The main object is to increase the general working efficiency of machines of this character, and at the same time to reduce the 25 number of parts and simplify the operations both of the rocking support and steam control.

One of the specific objects is to cause the head to be forced to its pressing position 30 and locked in that position, to release it from its locked position and to cause the application of steam to the garment, all through the medium of a single pedal lever, which may, therefore, be said to have a 35 triple function.

Another object is to enable the steam supply to the garment to be controlled independently of the pedal lever if desired.

A further object is to provide a more efficient and even distribution of the steam to the garment without necessitating the drilling of a large number of small holes for that purpose.

Other objects and uses relating to specific parts of the machine will be brought out in the following description.

In the drawings:

Figure 1 is a top plan and Fig. 2 a side elevation, partly in section, of a garment 50 pressing machine embodying the various features of my invention.

Fig. 3 is an enlarged detail sectional view taken on line 3-3, Fig. 1, showing more particularly the pedal operated steam controlling means.

Fig. 4 is a top plan of the lower pressing element, or buck, with the padding removed.

Figs. 5, 6 and 7 are sectional views taken, respectively, on lines 5-5, 6-6 and 7-7, Fig. 4.

Fig. 8 is a horizontal sectional view taken in the plane of line 8-8, Fig. 5.

Fig. 9 is an enlarged detail sectional view of the steam joint between the head and steam supply pipe, taken on line 9-9, Fig. 2.

Fig. 10 is an end view of one of the supporting yokes for one end of the steam joint pipe shown in Fig. 9.

Fig. 11 is an enlarged detail sectional view taken on line 11-11, Fig. 2, showing the yielding support for the front end of the main pedal lever.

As illustrated, the main supporting frame of this machine comprises an upright standard —1— having a relatively broad and flat supporting base —2—, the standard —1— having opposite upright parts in spaced relation through the great portion of their height, but united at the bottom to the base and at the top by a yoke —3—, the intermediate portions being connected at intervals by central cross-bars —4—, as shown in section in Fig. 2.

The standard —1— with its base —2—, yoke —3— and brace bars —4— is preferably formed integral of cast metal, and, together with a bracket —5—, constitute a main supporting frame for the various parts of the machine hereinafter described, the bracket —5— being secured to two of the uppermost brace bars —4— to project forwardly and upwardly therefrom, and is preferably chambered to receive certain pipes and valve operating mechanism hereinafter referred to.

The upright portion, as —5'— of the bracket —5— is disposed some distance in front of the upper portion of the standard —1— to allow sufficient intervening space for the manipulation of portions of the garment operated upon therein, the upper face of said extension —5'— being substantially flat for receiving and supporting the lower pressing element or buck —6— which is secured thereto by clamping bolts —6'—, and is therefore, stationary relatively to the frame with its upper face in a substantially horizontal plane and at a convenient height for receiving and supporting the garments.

to be operated upon. The upper face of the press head —6— is usually covered with a foraminous padding which is pervious to steam for distributing said steam more evenly over the entire area of the garment resting thereon.

The upper pressing element, as —7—, is mounted upon the front end of a lever or rock arm —8— which is hinged intermediately at its ends at —9— to the yoke —3— to swing vertically about a horizontal axis in substantially the same horizontal plane as the meeting faces of the buck —6— and head —7—, but some distance to the rear thereof so as to leave an intervening space sufficient for the proper manipulation of the clothes or garments over and upon and around the marginal edges of the buck.

The head —7— is resiliently connected to the front end of the lever —8— by means of bolts —10— and coil springs —11— at four different points to permit it to move relatively to and independently of its supporting arm —8—, and to thereby conform to varying thicknesses of material operated upon at different points throughout the area of the meeting faces of the pressing elements.

Head operating means.

A weight —12— is mounted upon the rear arm of the lever —8— and is adjustable toward and from the axis of the pivot —9— and is sufficient to normally over-balance the weight of the head —7— for automatically raising the latter away from the buck —6—, following the pressing operation, to such an angle as will permit free inspection and manipulation of the garment on the buck preparatory to pressing, said weight being held in its adjusted position by means of a clamping screw —13—.

The front end of the lever —8— is provided with a handle —14— by which it, together with the head —7— thereon may be moved vertically against or with the retracting weight when desired.

In machines of this character, it is necessary to provide means for bringing the head into pressing co-action with the buck with considerable pressure for producing the desired effect upon the garment, and, for this purpose is provided a toggle —15— and pedal lever —16—, together with suitable mechanisms whereby the same pedal lever may be utilized for breaking the toggle lock to release the press head from its pressing position, and also for operating a valve which controls the admission of steam to the garment, as will be hereinafter more fully explained.

The toggle —15— preferably consists of a pair of levers —17— and —18— pivoted to each other end to end at —19—, the lower lever —17— being fulcrumed or pivoted at

—20— to the standard —1— above the pedal at the rear of the vertical plane of the cross-bars —4— and preferably below the bracket —5—, the pivot —20— being located nearer the lower end than the upper end of the lever —17— to form a relatively long upper arm and a relatively short lower arm, which latter is provided with a weight —21— to assist in straightening the toggle to its locking position.

The upper end of the upper lever —18— is pivoted at —22— to a stud —23— which is adjustable endwise in a socket —24— in the rear end of the lever —8— just at the front of the weight —12— or between said weight and the pivot —9—, said stud —22— being provided with a threaded aperture engaged by an adjusting screw —25— having inner and outer collars —26— and —27— secured thereto and engaging the inner and outer faces of the outer end wall of the socket —24— for holding the screw against endwise movement relatively to the lever, the outer collar —27— constituting a hand wheel by which the screw may be turned to adjust the stud —23— in the socket —24—. The object of this adjustment is to regulate the period of locking of the toggle —15— relatively to the closing movement of the head —7—, or rather to vary the throw of the head to compensate for varying thicknesses of garments operated upon.

The connection between the toggle —15— and rear end of the lever —8— is some distance to the rear of the standard —1— and, therefore, when straightened or locked to hold the press head in its pressing position, it assumes an upwardly and rearwardly inclined position with both levers in substantially the same straight line, and the pivot —19— slightly inside or to the front of a straight line between the pivots —20— and —22—, the further forward movement of the toggle joint or pivot —19— being limited by suitable stop mechanism presently described.

For this latter purpose, the upper end of the lever —17— is provided with a forwardly projecting lug —28— carrying a threaded extension —29— which is screwed therein and is adjustable and held in its adjusted position by a lock nut —30—, the front end of the extension —29— being provided with a rubber tip —31— for engaging the rear face of the intermediate cross-bar —4—, and thereby limiting the forward throw of the toggle joint as the toggle is operated by the pedal lever —16— to force the press head to its pressing position, at which time the toggle levers will have assumed a substantially straight line, while the toggle joint —19— will have assumed a position slightly to the front of the straight line between the pivots —20— and —22—, where its further forward movement will be limited by the engagement of the part —31—

with the adjacent cross-bar —4— of the standard —1—.

The pedal lever —16— is preferably L-shaped to form a relatively long arm —32— and a shorter arm —33—, the longer arm —32— being disposed in a more or less horizontal position and is fulcrumed or pivoted at —34— to the standard —1— just above the base —2— and some distance below the fulcrum —20— of the toggle lever —17— so as to extend forwardly and rearwardly therefrom, the front end being provided with a pedal —35— projecting forwardly beyond the corresponding edge of said base and also slightly beyond the vertical plane of the pressing elements, where it is easily accessible to the operator when standing on the floor upon which the base of the standard —1— rests.

The shorter arm of the pedal lever —16— is disposed in a more or less vertical position at the rear of the fulcrum —34— and extends upwardly above the horizontal plane of the fulcrum —2— of the toggle lever —17— at the rear thereof and terminates in a horizontal plane between the fulcrum —20— and toggle joint —19— where it is provided with a contact roller —36— for engagement with the rear edge of the toggle lever —17— when the front end of the lever is depressed to effect the closing movement of the head —7— toward the buck —6—.

It will be observed, however, that the toggle —15— and pedal lever —16— have certain movements entirely independent of each other. For example, when the pedal lever is operated to force the toggle levers toward a straight position, the weight —21— may carry the toggle joint to its locking position in advance or independently of the complete operation of the pedal lever, while, on the other hand, when the toggle levers are forced to their locked position, the pedal lever may swing rearwardly away from the toggle lever —17— in a manner and for a purpose herein-after described.

The upright portion —33— of the pedal lever is considerably nearer to the fulcrum —34— than the pedal —35— which is of sufficient weight to overbalance the weight of the arm —33— and parts carried thereby, thereby tending to normally rock the front end of the lever downward, but this downward motion is limited by a yielding stop or vertically movable plunger —37— which is slidable vertically in a post —38— on the base —2— between the fulcrum —34— and pedal —35—, said post containing a coil spring —39—, Fig. 11, tending to force the plunger upwardly against an abutment —40— on the adjacent portion —32— of the pedal lever to normally hold the front end of said pedal lever in a slightly elevated position above the limit of its downward movement, and thereby to normally hold the con-

tact member —36— a short distance away from the rear edge of the toggle lever —17— when the head —7— is locked in its pressing position, the tension of the spring —39— being just sufficient to overcome the difference in weight between the front and rear ends of the pedal lever. In other words, the spring —39— through the medium of the plunger —37— and abutment —40— tends to yieldingly support the pedal lever in an intermediate position between its two extreme positions of adjustment, the rear end of said lever, preferably at the junction of the arms —32— and —33— being provided with a stop shoulder —41— for engagement with a rubber or other yielding abutment —42— on the base —2—, to limit the releasing movement of said lever and incidentally to limit the opening movement of the head —7— by the engagement of the rear edge of the toggle —15— with the contact member —36—, as shown more clearly by dotted lines in Fig. 2.

That is, when the toggle is unlocked to release the head —7—, the weight —12— raises the head and automatically flexes the toggle joint rearwardly and downwardly, during which operation, the rear edge of the toggle lever —17— engages the contact roller —36— and depresses the rear end of the pedal lever until limited by the engagement of the stop —41— with the abutment —42—, at which time the front end of the pedal lever will leave the plunger —37— and assume its extreme up position, as shown by dotted lines in Fig. 2, ready for a repetition of the pressing operation.

The press head —7—, together with its supporting lever —8—, toggle —15— and pedal lever —16—, is shown by full lines in the position which they assume during the pressing operation with pressure upon the pedal released, which allows the plunger —37— to rock the pedal lever upwardly and rearwardly from its extreme lower position until limited by the engagement of the head, —37'— of the plunger —37— with the inner end of an adjustable bushing, as —38'— in the post —38—.

This latter operation of the pedal lever by the plunger —37— is entirely independent of the toggle —15—, and, therefore, does not affect the pressing position of the press head —7— and its supporting lever —8—, said movement being sufficient to carry the contact roller —36— a short distance away from the rear edge of the lower toggle member —17—, where it is yieldingly held temporarily by the plunger spring —39—.

It, therefore, follows that the pedal lever may rock downwardly and forwardly a limited distance without causing the contact of the roller —36— with the toggle lever —17—, and this slight movement is utilized in a manner presently to be described for

flexing the toggle at the joint —19— rearwardly and downwardly to break the lock and release the head, and thereby to allow the weight —12— to rock the arm —8— with the head thereon away from the buck —6—, or to the position shown by dotted lines in Fig. 2, the opening of the head by the weight —12— also serving to rock the pedal lever to the extreme upward and rearward dotted position, as shown in the same figure.

For the purpose of flexing and releasing the toggle from its straightened locked position, a dog or pawl —43— is pivoted at —44— to the upright arm —33— of the pedal lever —16— and is provided with a forwardly projecting arm —45—, a downwardly projecting arm —46— and an upwardly projecting arm —47—.

The main body of the pawl —43— is in front of the pivot —44— and, therefore, tends to rock downwardly, but is restrained in this movement by a spring —48— engaging the rear face of the lower arm —46— below the pivot —44— and serving to normally keep the pawl in a substantially vertically position with its arm —45— projecting forwardly therefrom in close proximity to the rear edge of the weight —21— when the press head is closed upon the buck, or when the toggle is straightened and locked. The front end of the arm —45— normally rests on a slight projection —49— on the rear edge of the weight —21—, while, at the same time, the upper arm —47— lies directly under a rearwardly extending projection —50— on the toggle lever —17— just at the rear of the pivot —20—, the arm —47— being adjustable vertically on the main body of the pawl —46— to cause its proper coöperation with the projection —50—.

That is, assuming that the press head is released, and that it has assumed its extreme elevated position, as shown by dotted lines in Fig. 2, thereby effecting a corresponding movement of the toggle levers and pedal lever to produce a maximum separation of the pawl —43— and projection —50—, then as the pedal end of the lever is depressed by the foot of the operator to bring the head down upon the buck, the pawl —43— and projection —50— of the toggle lever —17— will approach each other in such relation that the rear end of the projection —50— will engage the front edge of the arm —47— and cause the front arm —45— of the pawl —43— to be rocked upwardly into registration with a recess —51— in the rear edge of the toggle lever —17— between the projection —50— and shoulder —49—, thereby causing the pawl —43— to rock upwardly and rearwardly to the position shown by dotted lines at the right of the arm —33—, Fig. 2, and will allow

the roller —36— to contact with the rear edge of the toggle lever —17— to force the toggle to a straightened position, where it is automatically locked by the straightening movement, which is aided materially by the weight —21— tending to hold the toggle in its locked position.

This brings the press head into pressing coaction with the buck to produce the desired pressure upon the garment. During this downward movement of the pedal end of the lever —16—, the latter is placed under slight lifting pressure by the depression of the plunger —37— against the action of the spring —39—, so that as soon as pressure upon the pedal —35— is released, the pedal lever is rocked upwardly and rearwardly to shift the roller —36— out of contact with the toggle lever —17—, as shown by dotted lines in Fig. 2, to the position shown by full lines, some distance to the rear of said toggle lever.

During this latter movement, the upper end of the arm —47— of the pawl —43— rocks downwardly by its own weight out of engagement with the rear end of the projection —50— and causes a similar movement of the arm —45— out of the recess —51— and against the stop shoulder —49— in close proximity to the rear of the weight —21—. Now, in order to break the toggle lock, it is simply necessary to apply slight downward pressure by the foot upon the pedal —35— which rocks the upright arm —33— of the pedal lever —16— forwardly and causes the arm —45— of the pawl —43— to engage the rear edge of the weight —21— below the pivot —20—, thereby forcing the toggle joint —19— rearwardly slightly beyond a direct line between the pivots —20— and —22— to break the toggle lock, the pressure upon the pedal —35— being then removed, if desired, to allow the press head to be rocked upwardly and rearwardly by the weight —12—, which also flexes the toggle joint —19— downwardly and rearwardly against the contact —36— on the rear arm —33— of the pedal lever to restore the same to its normal inoperative position ready for a repetition of the operation previously described.

Steam circulation and control.

The press head —7— is preferably hollow to form a steam chamber —52— to which steam is supplied from a pipe —53— through the medium of a swiveled coupling —54— and extension pipe —55—, the latter entering directly into the chamber —52—.

The rear end of the extension —55— and front end of the supply pipe —53— are provided with heads —56— having angular passages —57— therethrough for connection with the opposite ends of a similar pas-

sage —58— in the coupling —54—. The corresponding faces of opposite ends of the coupling —54— are provided with sockets —59— for receiving the adjacent ends of the heads —56— and suitable packing gaskets —60—, and also to permit the heads to turn freely in the sockets as the press head —7— and its supporting arm —8— are rocked toward and from the buck, and also to permit rocking movement of the head relatively to its supporting arm —8— with or against the action of the springs —11—. The heads —56— are provided with arms —61— carrying a hub —62— in spaced relation to, but coaxial with the heads for receiving between them the opposite ends of the coupling —54—. The ends of the coupling —54— are yieldingly held in engagement with the heads —56— by plungers —63— which are movable in the hub —62—, and are spring pressed against the adjacent faces of the ends of the coupling —54— by springs —64—, the tension of which may be adjusted by screws —65— engaging internally threaded portions of the hubs, as shown more clearly in Fig. 9.

This coupling and its connection with the heads —56— may be termed a steam joint, the parts of which when assembled are free to turn one upon the other, and are held in engagement to form steam tight joints by means of the plunger —63— and springs —64—, but may be readily separated by simply removing the adjusting screws —65—, which are easily accessible for adjustment or removal.

The buck —6— is preferably made of cast metal and is provided with an interior chamber or channel —66— extending entirely around the marginal edge thereof to form a heating chamber, said head being also provided with a primary distributing chamber —67— and a secondary distributing chamber —68— through which steam is admitted to the garment for moistening purposes.

A downwardly extending steam supply pipe —69— is connected to the main supply pipe —53— and is provided with a branch pipe —70— leading to an inlet —71— in the underside of the buck. The inlet —71— communicates with a channel —72— running a short distance along the inner side of a partition —73— between said channel and chamber —66— and communicating with such chamber through a passage —74— over the upper edge of the partition —73— which rises from the bottom of the chamber —66— and channel —72— to a horizontal plane just sufficiently below the top of said chamber and channel to form the connecting passage —74—. The object of this partition —73— is to produce a collecting chamber for water of condensation in the adjacent portion of the

chamber —66— to prevent such water from passing into the distributing chambers —67— and —68—.

The end of the channel —72— opposite that at which the inlet —71— is located is provided with a forwardly extending branch —72'— leading to a vertical valve chamber —75— at the longitudinal center of the buck and extending through the top thereof, where it is closed by a plug —76—.

An upright tubular valve case —77— is secured in the lower end of the valve chamber —75— and is provided with a valve seat —78— normally engaged by a ball valve —79—, said valve case being provided with one or more radial steam passages —80— through the peripheral walls thereof just above the center of the valve, when the latter is closed, to communicate with the surrounding chamber —75—, so that when the valve is raised from its seat, the live steam passes from said valve chamber through the ports —80— and thence through the opening in the bottom of the valve case to an underlying chamber —81— which communicates through upwardly diverging passages —82— with the distributing chambers —67—, as shown more clearly in Fig. 5, thereby admitting the live steam to the primary distributing chamber and thence through passages —83— to the secondary distributing chamber —68—.

This distributing chamber —68— preferably consists of a chain of, in this instance five, relatively small circular chambers arranged side by side lengthwise of and in the upper portion of the buck with their adjacent sides merging with each other, as represented more clearly in Fig. 4, for receiving a similarly formed plate —84—, which is of slightly less area than that of the chamber in which it is located to form relatively narrower steam exit passages —85— and —86— at the inner and outer edges of the chain of rings forming the plate —84—, said plate being secured to the upper face of the buck by screws —87— or equivalent fastening means.

A drain pipe —88— leads from the bottom of a portion of the heating chamber —66— directly opposite the inlet —71— and is connected to an extension —89— of the pipes —69— to drain off water of condensation through a main drainage pipe —90—.

A valve operating rod —91— is movable vertically in a suitable guide opening in the upper portion of the bracket —5— which supports the buck —6—, the upper end of said valve being provided with a stop shoulder —92— adapted to engage the upper face of the adjacent portion of the bracket —5— for limiting the downward movement of said rod so that its upper end may lie in close proximity to the underside of the valve —79—. The lower end of the valve oper-

ating rod —91— is surrounded by a coil spring —93— which is interposed between the underside of the adjacent portion of the bracket —5— and a shoulder —94— on the 5 rod to normally force the latter downwardly away from the valve with its shoulder —92— resting on the adjacent portion of the bracket.

A separate valve operating rod —95— is 10 movable vertically in a suitable guide —96— in the bracket —5— coaxial with the rod —91— and has its upper end normally lying in close proximity to the underside of the shoulder —94—, while its lower end rests 15 upon the rear end of a supplemental pedal lever —97— which is fulcrumed at —98— upon the base —2— at one side of, but in close proximity to the main pedal lever —16—, where both levers may be conveniently operated by simply shifting the foot 20 from one pedal to the other.

The intermediate portion of the valve operating rod —95— is surrounded by a coil spring —99— having one end bearing 25 against the underside of the guide —96— and its other end engaged with an adjustable collar —100— on the rod —95— to normally force said rod downwardly on to the pedal lever —97—.

30 The function of this pedal lever —97— is to control the position of the valve —79— through the medium of the rods —91— and —95— and springs —93— and —99— and to thereby control the supply of steam to the 35 garment for moistening purposes. It is however, desirable to provide means whereby this supply of steam for moistening purposes may be controlled by the main pedal lever —16— at the same time that the press head is 40 brought into pressing engagement with the garment, and for this purpose the front end of the lever —97— is provided with a transverse guide opening —101— for receiving a coupling rod —102— which is slidable horizontally in the guide opening —101— to and 45 from a position directly under the front end of the main pedal lever —16—.

In Fig. 3, the rod is shown by full lines 50 as adjusted to cause the operation of the pedal lever —97— by the depression of the front end of the main pedal lever —16—, the dotted lines indicating its position when withdrawn from beneath the main pedal lever. This underlying position of the coupling rod —102— relatively to the main lever —16— permits the pedal lever —97— to be operated independently of the main lever when the head is open, and also when it is closed upon the garment and locked by the 55 toggle levers, or the rod —102— may be withdrawn or forced out from under the pedal lever —16— by the foot to permit the latter to be depressed to the limit of its downward movement without affecting the 60

operation of the pedal —97— or valve controlled thereby.

The plunger —37— previously referred to is adjusted to elevate the forward end of the pedal lever —16— a short distance above the underlying rod —102— when the head —7— 70 is forced to its pressing position and the valve —79— closed, at which time, the pawl —46— will have assumed the position shown in Fig. 2 ready to engage the rear edge of the weight —21— of the toggle lever —17—, the 75 clearance between the rod —102— and lower side of the front end of the pedal lever being sufficient to allow the pedal to be operated to release the toggle levers from their locking positions without operating the pedal lever —97— or opening the valve —79— when it is desired to permit the head —7— to be rocked upwardly and rearwardly away from the buck through the medium of the weight —12— and rocking support —8—, which, in 80 turn, causes the pedal lever —16— to be restored to its starting position, as shown by dotted lines in Fig. 2.

Operation.

Assuming now that the press head and its operating means are in their starting position with the press head full open and the steam valve —79— closed, the garment to be pressed is then laid out upon the upper surface of the buck and properly smoothed by hand preparatory to pressing, whereupon the press head may be forced to its pressing position by downward pressure of the foot upon the pedal —35—, which causes the contact roller —36— to engage the rear edge of the toggle lever —17— for forcing the toggle to its straightened position aided by the weight —21— which causes the toggle joint —19— to assume a position slightly at the 95 front of a straight line between the pivots —20— and —22— for locking the press head in its pressing position.

As the downward movement of the front end of the pedal continues, it engages and 100 depresses the plunger —37— against the action of the spring —39—, and also engages and depresses the underlying rod —102— and front end of the supplemental pedal —97— for opening the valve —79— through 105 the medium of the rods —95— and —91—, thereby admitting steam to the chamber —66— through the passage —74—, and also admitting steam through the channel —72— to the valve chamber —75—, and thence 110 through the passages —77—, chamber —81— and passages —82— to the distributing chambers —67—, from which the steam passes through the ports —83— to the secondary distributing chamber —68— and out 115 through the passages —85— to the overlying pad and garment thereon for moistening purposes.

This extreme downward pressure of the front end of the pedal lever —16— is maintained only for an instant, just sufficient to allow a blast of steam to be directed to the 5 garment, whereupon the pressure thereon is released to allow the plunger —37— to elevate the front end of the pedal lever —16— away from the underlying rod —102—, which permits the supplemental pedal 10 —97— and valve controlled thereby to return to their normal position to shut off the supply of steam to the garment. The press head being now located in its pressing position by the straightening of the toggle—15— 15 permits the lever —97— to be operated independently as often as may be desired to supply additional steam to the garment without disturbing the main pedal lever —16—. On the other hand, after the pressing and 20 moistening operations are completed, a slight downward pressure upon the pedal —35— will cause the arm —45— of the pawl —43— to rock the lower end of the toggle lever —17— forwardly, thereby flexing the 25 joint —19— rearwardly to break the toggle lock so that by relieving the pressure upon the pedal —35—, the weight —12— will restore the press head —7— and its operating means to their normal or starting 30 position, it being understood that the steam admitted to the chamber —66— of the buck and also to the chamber —52— of the press head serves to keep those pressing elements heated to a sufficient degree to accelerate the 35 drying of the garment immediately following the pressing and moistening operations.

If necessary, the steam chamber —52— of the press head may be provided with an air vent —103— controlled by a valve —104— 40 to prevent said chamber from becoming air bound, or rather to relieve it from air so that the steam may readily flow therein.

Although the mechanisms shown and described are found to be highly efficient, it is 45 evident that various changes may be made in the detail construction without departing from the spirit of this invention, and, therefore, I do not wish to limit myself to that particular construction.

50 What I claim is:

1. In a machine for pressing garments, coöperative pressing elements, one of which is movable toward and from the other, and means for operating the movable element including a toggle and a pedal lever operating against one of the toggle members for forcing the toggle to a straightened position, and thereby locking the movable element in its pressing position, said pedal lever being 55 movable independently of the toggle after the latter has been forced to its locked position, in combination with means actuated by the independent movement of said pedal lever in one direction for flexing the toggle 60

and thereby releasing it from its locking position. 65

2. In a garment pressing machine, the combination of coöperative pressing elements, one of which is movable toward and from the other, means for admitting steam 70 to a garment between the pressing elements, means including a pedal lever movable to one position for forcing the movable element to its pressing position and having an independent movement irrespective of the 75 movable element, a valve for controlling the supply of steam to the garment, and means actuated by the independent movement of the pedal lever for opening said valve.

3. In a garment pressing machine, a 80 frame, coöperative pressing elements, one of which is movable toward and from the other, a rocking support for the movable element, toggle connections between said support and frame, a pedal lever for straightening the 85 toggle to force the movable element to its pressing position and having an independent movement relatively to the toggle, and means actuated by the independent movement of the pedal for flexing the toggle to release 90 the movable element from its flexing position.

4. In a garment pressing machine, a 95 frame, coöperative pressing elements, one of which is movable toward and from the other, a rocking support for the movable element, toggle connections between said support and frame, a pedal lever for straightening the toggle to force the movable element to its pressing position and having an 100 independent movement relatively to the toggle, means for conducting steam between said elements for moistening purposes, a valve controlling said steam, means actuated by said pedal for opening the valve, and means actuated by the independent movement of the pedal for flexing the toggle to release the movable element from its pressing position. 105

5. In a garment pressing machine, the 110 combination of a frame, coöperative pressing elements, one of which is movable toward and from the other, a rocking support for the movable element, means for operating the rocking support to carry the 115 movable element away from the other element, toggle connections between the rocking support and frame, a pedal lever for straightening said toggle to force the movable element into pressing coaction with the other element, means for causing a partial return movement of the pedal lever independently of the toggle after the toggle has been straightened, and means actuated by a further movement of the pedal for engaging and flexing the toggle to release the movable element from its pressing position. 120

6. In a garment pressing machine, coöp-

erative pressing elements, one of which is movable toward and from the other, a pedal lever, means actuated by the movement of the pedal lever in one direction for forcing the press head to its pressing position, means for moving the pedal lever in an opposite direction independently of the first named means, and additional means actuated by the movement of the pedal lever in the first 10 named direction for operating the first named means to release the movable element from its pressing position.

7. In a garment pressing machine, coöperative pressing elements, one of which is movable toward and from the other, a pedal lever, means actuated by the movement of the pedal lever in one direction for forcing the press head to its pressing position, means for moving the pedal lever in an opposite direction independently of the first named means, additional means actuated by the movement of the pedal lever in the first 20 named direction for operating the first named means to release the movable element from its pressing position, means for conducting steam to the garment for moistening purposes, a valve controlling the steam, and means actuated by the movement of the pedal lever in the first named direction for 25 opening the valve.

8. In a garment pressing machine, the combination of a frame, coöperative pressing elements, one of which is movable toward and from the other, a rocking support 35 for the movable element, a toggle having one of its levers pivoted to the frame and its other lever connected to the rocking support, means tending to force the toggle toward its position for closing the movable element upon the other element.

40 9. In a garment pressing machine, the combination of a frame, coöperative pressing elements, one of which is movable toward and from the other, a rocking support 50 for the movable element, toggle connections between the frame and support, means tending to straighten the toggle to close the movable element upon the other element, additional means tending to flex the toggle 55 to open the movable element away from the other element, means for stopping the movement of the toggle at substantially its straightened position, and pedal operated means for straightening the toggle.

60 10. In a garment pressing machine, the combination of a frame, a horizontal buck mounted on the frame, a lever of the first kind fulcrumed on the frame to swing about a horizontal axis substantially parallel with 65 the longitudinal center of the buck and some

distance to the rear thereof, a press head mounted on the front end of the lever to move toward and from the buck, a weight on the rear end of the lever for over-balancing the weight of the head and raising the 70 latter away from the buck, a toggle connection between the frame and rear arm of the lever and having its members movable to a substantially straight line for closing the head upon the buck, said toggle members 75 flexing rearwardly from their straightened position to withdraw the head away from the buck, a weight on one of the toggle members for moving said members toward a straightened position, a pedal lever operable in one direction for straightening the toggle, means for moving the lever in an opposite direction independently of the toggle, and a pawl on the pedal lever for engaging and flexing the toggle from its 80 straightened position when the pedal lever is operated in one direction independently of the toggle.

11. In a garment pressing machine, the combination of a frame, coöperative pressing elements, one of which is movable toward and from the other, means including a toggle and an actuating pedal lever therefor for forcing the movable element to its pressing position, said toggle having one of its 90 members fulcrumed on the frame of the machine to swing about a horizontal axis, a pedal lever being also fulcrumed on the frame of the machine some distance below the toggle to move about a horizontal axis 95 and having its forward end provided with a pedal and its rear end extending upwardly at the rear of said toggle member to engage the same above the fulcrum thereof.

12. In a garment pressing machine, the combination of a frame, coöperative pressing elements, one of which is movable toward and from the other, means including a toggle and an actuating pedal lever therefor for forcing the movable element to its 100 pressing position, said toggle having one of its members fulcrumed on the frame of the machine to swing about a horizontal axis, a pedal lever being also fulcrumed on the frame of the machine some distance below the toggle to move about a horizontal axis 105 and having its forward end provided with a pedal and its rear end extending upwardly at the rear of said toggle member to engage the same above the fulcrum thereof, said 110 pedal lever being movable independently of the toggle, and means actuated by an independent movement of the pedal lever for engaging said toggle member below its fulcrum to flex the toggle from its straightened position.

13. In a garment pressing machine, the combination of a frame, a buck mounted thereon, a press head movable toward and from the buck, a supporting lever for the 115 120 125 130

- press head fulcrumed intermediate its ends, toggle connections between the frame and rear end of said lever and having one of its members fulcrumed on the frame to swing 5 about a horizontal axis, a pedal lever of the first kind fulcrumed on the frame to swing about a horizontal axis and having its front end provided with a pedal and its rear end extended upwardly at the rear of said toggle 10 lever above the fulcrum thereof for engaging the same and forcing the toggle toward a straightened position when the pedal is rocked downwardly, said pedal lever having an independent movement relatively to the 15 toggle, and means actuated by the pedal lever when moved independently of the toggle for engaging said toggle member below its fulcrum to flex said toggle from its straightened position and thereby to release 20 the head from its pressing position.
14. In a garment pressing machine, co-operative pressing elements, one of which is movable toward and from the other, means including a pedal lever for forcing the mov- 25 able element toward the other element, means for conducting steam to one of the pressing elements for moistening the garment, a valve for controlling the steam, a pedal lever for operating said valve and 30 means for transmitting motion from the first named lever to the second named lever for opening the valve simultaneously with the operation of the first named lever to bring the movable element into pressing co-action with the other element. 35
15. In a garment pressing machine, co-operative pressing elements, one of which is movable toward and from the other, means including a pedal lever for forcing the movable element toward the other ele- 40 ment, means for conducting steam to one of the pressing elements for moistening the garment, a valve for controlling the steam, a pedal lever for operating said valve and means for transmitting motion from the first 45 named lever to the second named lever for opening the valve simultaneously with the operation of the first named lever to bring the movable element into pressing co-action with the other element, said last 50 named means including a member on the second named pedal lever movable into and out of the path of movement of the first named pedal lever. 55

In witness whereof I have hereunto set my hand this 18th day of September, 1920.

RICHARD H. MELZER.
